UNITED STATES PATENT OFFICE.

JOHN M. HOPWOOD, OF DORMONT, PENNSYLVANIA, ASSIGNOR TO THE HAGAN CORPORATION, OF PITTSBURGH, PENNSYLVANIA, A CORPORATION OF PENNSYLVANIA.

STORAGE-TANK.

1,400,747.

Specification of Letters Patent. Patented Dec. 20, 1921.

Application filed December 8, 1919. Serial No. 343,418.

To all whom it may concern:

Be it known that I, JOHN M. HOPWOOD, residing at Dormont, in the county of Allegheny and State of Pennsylvania, a citizen 5 of the United States, have invented or discovered certain new and useful Improvements in Storage-Tanks, of which improvements the following is a specification.

The invention described herein relates to 10 certain improvements in tanks for disintegrated materials such as ashes, etc., and is especially adapted for use in pneumatic conveying systems and has for its object a construction and combination of means for 15 facilitating the discharge of ashes or other material from the tanks.

In the accompanying drawings forming a part of this specification, Figure 1 is the sectional elevation of a tank for ashes, etc., 20 embodying the improvements contained herein. Fig. 2 is a plan view of the lifting head, and Fig. 3 is a view similar to Fig. 1 illustrating certain modifications.

In the combination shown in Fig. 1, the 25 tank 1 which is usually made of metal, is provided at its upper end with an inlet opening over which is generally arranged a target box 2, and with a discharge opening at its lower end, the lower portions of the 30 walls of the tank inclining inwardly and downwardly, as shown, to facilitate the movement of the ashes to the discharge opening, which will be normally closed by any suitable means as a swinging door 3.

It has been found that the clinker, ashes, etc., will become knit together and form an arch across the tank of sufficient strength 35 to sustain the weight of the material above. When tanks are provided with central discharge openings, as shown in Fig. 1, the material adjacent to the axis of the tank will move more rapidly than portions adjacent to the sides and the pressure on the center of the arch and the support given the 40 edges by the slower moving or stationary portions at the sides of the tank, result in rendering the arch stronger and more difficult to dislodge with a poker or other means inserted through openings in the upper and 45 lower ends of the tank.

The invention described herein has for its object the provision of means for imparting an upward movement of a core of the material in line with the discharge opening 50 from the tank, thereby permitting a freer

movement of the material adjacent to the sides of the tank or around the core. This upward movement of the core will attack the arch at a point and in a direction least capable of resistance and the downward movement at the sides of the tank will destroy the peripheral support of the arch. Provision is also made for causing the core of material to move laterally or toward the sides of the tank in passing around the core 60 support toward the discharge opening. It is characteristic of the improvement claimed herein that provision is made for facilitating the movement of those portions of the material, *i. e.*, the portions adjacent to the 65 sides of the tank which serve as abutments for any arch formed in the tank and by the removal of such support the arch itself will be broken up. And further, by applying upward pressure to the central portion of 70 the arch through the central core, the destruction of the arch is insured.

A convenient means for effecting the upward movement of a core of material in line with the discharge opening, consists of a 75 cone shaped block 4 provided with a plurality of radial wings 5 and means for moving the block away from the discharge opening. A convenient means for moving the core consists of a rope or chain having one 80 end connected to the apex of the core and its opposite end connected to a drum 7 on a shaft mounted in suitable bearings in the sides of the tank. One end of the shaft projects outside of the tank and on this projecting end is secured an operating handle 8. If desired a pawl and ratchet may be 85 employed for maintaining the core in any desired position in the tank.

Normally, the points of the wings will rest 90 on the inclined surfaces of the tank adjacent to the discharge opening. When the cone is raised the projecting wings will loosen up the material adjacent to the discharge opening so that it will flow freely from the tank. 100

The flow or movement of the portions of the material forming the peripheral support for arching may be promoted by forming the tank with outwardly flaring or inclined walls as shown in Fig. 2. In such construction the bottom 9 of the tank would be formed preferably at an angle substantially greater than the angle of repose of the material to be stored in the tank and would 105 extend entirely across the tank to the dis- 110

charge spout 10. As there may at times be a clogging or retardation of flow of a material where the walls incline inwardly, to direct the material toward the discharge opening, it is preferred to provide holes 11 through the walls at suitable points for the insertion of rods for breaking up any agglomeration of the material. In order to prevent a continual discharge of material from the openings, shelves 12 extend outwardly from points below the openings. Materials passing through the openings will lodge on the shelves and soon form dams which will prevent further movement through the openings.

In the construction shown in Fig. 1, the flow of the portions of the charge adjacent to the walls of the tank is promoted by checking or retarding the movement of the central core so that on opening the outlet the outer portions will be free to flow under the supported central core. This acceleration of the flow of the outer portions of the charge will be further promoted by the flaring or outward inclination of the side walls of the tank as shown in Fig. 2. In other words, the more rapid flow of the outer portions is due to the retardation or prevention to a greater or less degree of the movement of the inner central portion, while by flaring the walls of the tank the outer portions are free to loosen up and in consequence of such loosening up will flow more rapidly toward the central portions. Hence it is preferred to use both means, one acting cumulatively on the other.

I claim herein as my invention:

1. A tank for ashes, etc., provided with an outlet at its lower end, in combination 40 with a door for such outlet, means arranged

within the tank and adapted to so control the movement of the material through the tank that the flow of material adjacent to the wall of the tank will be more rapid than the inner or central portions of the mass 45 contained in the tank and means for raising and lowering the retarding means.

2. A tank for ashes, etc., provided with an outlet at its lower end in combination with a door for such outlet, means independent of the door for retarding the movement of a core of material toward the outlet opening, means for raising and lowering the retarding means.

3. A tank for ashes, etc., provided with an outlet at its lower end, and having downwardly inclined sides in combination with a door for such outlet, means independent of the door for retarding the movement of a core of material toward the outlet opening, 60 means for raising and lowering the retarding means.

4. A tank for ashes, etc., provided with an outlet at its lower end in combination with a door for such outlet, means independent 65 of the door for lifting a core of material to permit a free movement of material outside of the core toward the outlet opening and means for raising and lowering the core lifting means.

5. A tank for ashes, etc., provided with an outlet at its lower end in combination with a door for such outlet, and a conical block and means for moving said block upwardly whereby the material above the outlet is loosened to facilitate its movement 75 from the tank.

In testimony whereof I have hereunto set my hand.

JOHN M. HOPWOOD.
